UNITED STATES PATENT OFFICE.

MARTIN J. SCHENK, OF CHICAGO, ILLINOIS.

CRANK-SHAFT.

1,347,178.

Specification of Letters Patent. Patented July 20, 1920.

Application filed February 27, 1919. Serial No. 279,529.

To all whom it may concern:

Be it known that I, MARTIN J. SCHENK, a citizen of the United States, residing at Chicago, in the county of Cook and State 5 of Illinois, have invented certain new and useful Improvements in Crank-Shafts, of which the following is a specification.

This invention relates to improvements in crank shafts and the bearings associated 10 therewith.

One object of the invention is to provide a crank shaft which shall be made up of a plurality of detachable parts, any one of which may be readily and quickly removed 15 should repairs or replacement become necessary, thereby dispensing with the removal of the entire crank shaft and the many disadvantages incident thereto, and also avoiding the expense of replacing the entire 20 crank shaft such as is now occasioned in internal combustion engines wherein solid crank shafts are used when such crank shafts become worn beyond repair, fractured, or otherwise rendered inoperative.

Another object of the invention resides 25 in the provision of a novel form of adjustable antifriction bearing for crank shafts and for the connecting rods attached thereto.

A further object is to provide a crank 30 shaft having detachable crank pins, whereby the same may be readily and quickly removed, together with the attached connecting rods and pistons, independently of 35 the crank shaft as a whole.

Other objects and advantages will become apparent from the following description, taken in connection with the accompanying drawings, wherein one form of the 40 invention is illustrated.

Figure 1 is a vertical sectional view taken through the crank case of an internal combustion engine, showing my improved crank shaft mounted in operative position 45 therein;

Fig. 2 is a sectional view taken on the line 2—2 of Fig. 1;

Fig. 3 is a detailed view, partly in section, showing the application of my invention to an internal combustion engine of the V-type; and

Fig. 4 is a sectional view taken on the line 4—4 of Fig. 3.

The present improvements have been 55 signed primarily for use in connection with internal combustion engines of the type

used in the propulsion of vehicles, aeroplanes, and the like, but it will be obvious from the following that the invention is not limited in scope to such use, but, on the other hand, may be used substantially where any crank shaft is employed. In Fig. 1 of the drawings a crank shaft, constructed in accordance with the present invention, is shown mounted in operative position within the crank case of an internal combustion engine, the crank case being broken away, as shown, in order to indicate that as many cranks may be provided on the shaft as desired, depending, of course, upon the number of cylinders provided in the particular engine in connection with which it is desired to use the shaft. In this figure of the drawings, only two cranks are shown in order to simplify the illustration.

Referring more in detail to the drawings, the crank case is shown at 10, and preferably comprises an upper section 10^a apertured across the top to permit of the pistons extending upwardly into their respective cylinders, and a lower section 10^b which is secured in any suitable manner to the section 10^a and which forms with said section 10^a a complete housing for the crank shaft and associated parts.

The crank shaft is illustrated at 11, and is shown supported by three main bearings 12, one provided in each end of the crank case, and one interposed centrally between the two ends of the crank case, substantially as shown. The crank shaft 11 preferably comprises a plurality of main shaft sections 13 to the adjacent ends of which are attached removable crank arms 14. Each of the crank arms is provided with two oppositely disposed transverse V-shaped channels 15 and 16, the channel 15 being designed to receive one end of one of the main shaft sections 13, said section being clamped securely within said channel by means of the retaining block 17 and screw-threaded bolts 18. The end of the shaft section 13, which is thus clamped within the channel 15, is preferably provided with oppositely disposed grooves 19, through which the bolts 18 extend when placed in position. The ends of the bolts preferably screw-threadedly engage the crank arm 14, and in addition are provided with nuts 20. In order that the grooves 19 provided in the end of the shaft section 13 may aline properly with the bolt holes provided in the crank arm 14

and the clamping block 17 when said shaft section 13 is in position within the channel 15 of said crank arm, the end of said shaft section is provided with a dowel pin 21, or 5 other suitable centering device which is adapted to seat within a suitable socket provided in the bottom of the channel 15. In this manner, the crank arm may be readily and quickly attached to the end of 10 the shaft section.

The channel 16 which is provided in the opposite face of the crank arm 14 is located adjacent the end of the crank arm opposite to the end in which the channel 15 is provided, and is adapted to receive the end of 15 the crank pin 22, said crank pin being clamped securely in position within the channel 16 in substantially the same manner as the shaft section 13 is clamped within its 20 channel 15, namely, by means of a clamping block 23 and bolts 24, the bolts 24 screw-threadedly engaging the crank arm 14 and extending through oppositely disposed grooves 25 provided in the pin 22. A 25 dowel pin 21^a is also provided, so that the pin 22 may be positioned within the channel 16 in such wise that the grooves 25 align properly with the bolt holes provided in the block 23 and crank arm 14. The two 30 crank arms of each of the cranks of the crank shaft are attached at their opposite ends, respectively, to the ends of the crank pin 22, which is common to said crank arms, and to the adjacent ends of the corresponding 35 shaft sections in the manner above set out. It will be readily observed that by providing the channels 15 and 16 of the crank arm 14 in opposite faces thereof that the turning stresses imparted to the crank 40 shaft by the connecting rod are transmitted directly to the shaft through the crank arm. In other words, the channels are so arranged that upon a forward driving of the shaft, the turning moments are applied directly 45 to the crank arm, as distinguished from an application thereof in the reverse direction which would bring the force thereof to bear against the clamping blocks 17 and 23.

50 The connecting rods, shown at 26, are preferably constructed integral, the lower ends thereof being enlarged, as shown at 27, and being provided with an opening extending therethrough, through which openings 55 the corresponding crank pins 22 are adapted to extend. The openings provided in the enlarged lower ends 27 of the connecting rods are of larger diameter than the diameter of the crank pins, so that an interposed housing is provided for the anti-friction bearings. These bearings each 60 comprise an inner and outer raceway 28 and 29, respectively, the outer raceway 29 comprising a plurality of conically tapered 65 rings 30 fixed within the opening provided

in the enlarged end 27 of the connecting rod, while the inner raceway comprises a plurality of similarly tapered rings 31 which are mounted on the crank pin 22 and adapted to rotate therewith. Interposed between the two raceways 28 and 29 are a plurality of doubly tapered roller bearings 32, preferably in the form of double truncated cones, the opposite ends of each of these roller bearings extending between a pair of the rings 30 and 31. A suitable spacing element 33, similar to the "squirrel cage" commonly provided in anti-friction bearings, is provided in the present bearing in order to maintain the rollers 32 properly spaced 70 apart. The enlarged end 27 of the connecting rod is preferably provided with an overhanging flange 34, designed to maintain the raceway 29 against lateral displacement in one direction, while at the other side of the 75 head 27 a removable locking ring 35 is provided, designed to maintain the raceway 29 against lateral displacement in the other direction. In placing the bearing in the position shown in the drawings, said bearing, 80 as a unit, is forced into the housing provided in the head 27 of the connecting rod and into contact with the annular overhanging flange 34, after which the locking ring 35 is secured in the position shown. 85 The crank pins are preferably screw threaded on each side of the bearing adjacent thereto, and suitable nuts 36 are provided, whereby the bearing and connecting rod may be properly centered on the pin by 90 moving the same longitudinally thereof. 95 From this construction, it will also be observed that should the bearings become worn, the same may be readily and quickly tightened up by merely adjusting the nuts 100 36 toward each other, thus forcing the rings 31 of the raceway 28 inwardly and thereby wedging the roller bearings 32 into firm engagement between said rings 31 and the rings 30 forming the outer raceway 29. It 105 is preferred to provide some suitable locking means, such as shown at 37, for the nuts 36. On the lower side of the enlarged end 27 of each of the connecting rods is provided an oil dip 38, by means of which oil 110 is scooped from the bottom of the crank case during each revolution of the shaft and conveyed from the dip 38 upwardly through the duct 39 to the bearing.

115 The main center bearing 12 is the same in 120 construction as the connecting rod bearings just described, and accordingly the description of the latter applies equally as well to the former. As will be observed from Fig. 1 of the drawings, this center main bearing 125 is contained within the housing 40, which housing is suspended from the top wall of the crank case section 10^a, as shown. The two end main bearings are also of the same construction as the connecting rod bearings, 130

with the exception that only one adjusting nut 41 is provided. It will be observed, however, that an adjustment of the rings of the inner raceway 28 of these bearings may 5 be effected by the adjusting nut 41 to compensate for any wear that may take place in substantially the same manner in which an adjustment of the connecting rod bearings is effected. On the inner side of each of 10 these main end bearings, there is provided a suitable spacing element 42 against which the adjacent crank arm bears. The housing for each of these main bearings is, as with the connecting rod bearings, provided with 15 an integral retaining flange 43 and a removable locking ring 44.

In Fig. 3 of the drawings is shown a detailed fragmentary view, partly in section, disclosing the method of adapting a crank 20 shaft constructed in accordance with the present invention for use in connection with internal combustion engines of the so-called V-type. In this view, one crank of the shaft is shown and two connecting rods, one from 25 each of the corresponding cylinders of the adjacent series attached to the crank pin of said crank, a bearing of the type hereinbefore described being provided for each of the connecting rods, and a suitable spacing 30 element 45 being interposed between the bearings substantially as shown. The bearings in this construction are the same as those hereinbefore described, and are adjustable by means of the nuts 46, by means 35 of which nuts the connecting rods may also be properly centered relatively to their respective cylinders.

From the foregoing, it will be observed 40 that a multiple section crank shaft has been provided which may be readily assembled and disassembled, and one which permits of any one of its various parts being readily and quickly removed for purposes of repair or replacement. It will be further observed 45 that in the event it is desired for any reason to remove one of the connecting rods, together with the piston attached thereto, that such removal may be effected by merely removing the lower section 10^b of the crank 50 case and then removing the bolts 24 and clamping block 23 at each end of the crank pin, after which the crank pin, bearing, connecting rod and piston may be quickly and entirely removed from the engine as a unit.

It will also be observed that should the bearings, after long continued use, become worn 55 to any degree that by merely removing the lower section 10^b of the crank case said bearings may be quickly adjusted, so as to compensate for such wear by merely tightening 60 up on the adjusting nuts 36. This adjustable feature, as above pointed out and as is apparent from the drawings, is also present in each of the main bearings of the crank 65 shaft, and, accordingly, these bearings may also be adjusted to compensate for any wear which may occur. It will also be apparent from the multiple section construction of the crank shaft, and particularly from the construction of the crank arms, that any one 70 of the cranks of the shaft may be entirely removed without interfering with or disassembling any of the other portions of the crank shaft. In other words, all of the parts of the shaft are quickly removable and readily replaceable, so that if, due to various reasons, a part of the shaft is rendered useless, such part and such part only need be replaced in order to render the crank shaft again operable. It will be further noted 75 that by reason of the anti-friction bearings, herein described, that wear upon the main shaft sections and the crank pins, as well as on the connecting rods and crank case, is completely avoided, and that by reason of 80 the quickly removable nature of the bearings the same, should they become broken or otherwise rendered inoperative, may be quickly replaced without necessitating a removal of anything from the structure but 85 the bearing which it is desired to replace. In view of the above, the many advantages of the present construction over crank shafts as heretofore constructed will be apparent.

It is obvious that various changes and modifications may be made in the particular embodiment of the invention herein illustrated without departing from the spirit of the invention, and it is not therefore desired to limit the invention to such embodiment or to the particular adaptation of the embodiment shown in the drawings, except where limitations appear in the appended claims.

What I claim is:

1. In combination, a crank shaft having a detachable crank pin, a connecting rod attached to said pin, and means for laterally adjusting said connecting rod on said pin in either direction.
2. A crank shaft comprising a plurality of main shaft sections, crank arms having transverse channels therein adjacent the inner ends thereof adapted to receive adjacent ends of said shaft sections, other transverse channels provided adjacent the outer ends of said crank arms, and a crank pin detachably secured in said last named channels.
3. In combination, a crank shaft, a connecting rod having an enlarged opening through one end thereof adapted to receive the horizontal portion of the crank of said shaft, a raceway supported around the wall of said opening, another raceway on the said horizontal portion of said crank adjacent said first raceway, roller bearings interposed between said raceways, means carried by said connecting rod for maintaining said first raceway against accidental displacement, and adjustable means on the said

horizontal portion of said crank in engagement with said second raceway, whereby said bearing, together with said connecting rod, may be adjusted longitudinally of said horizontal portion.

4. A crank shaft comprising a plurality of main shaft sections, a crank pin, crank arms having channels formed in the opposite faces thereof and adjacent the ends thereof adapted to receive the adjacent ends of said shaft sections and the ends of said pin, respectively, and means for clamping said crank arms in operative position.

5. A crank shaft comprising a plurality of main shaft sections, a crank pin, S-shaped

crank arms adapted to receive within their oppositely disposed channels the ends of said pin and the adjacent ends of said sections, respectively, and clamping blocks detachably secured in said channels for holding said arms in operative position, said arms being mounted in such wise that the forward driving thrusts imparted thereto through said pin are applied directly against said arms in the direction of the pin-receiving channels, whereby undue strain on said blocks is avoided.

In testimony whereof I have subscribed my name.

MARTIN J. SCHENK.
